Inventor
Ora A. Runkle
By Hiram Schwartz, Atty.

UNITED STATES PATENT OFFICE.

ORA A. RUNKLE, OF WOOSTER, OHIO.

BRUSH.

Application filed May 15, 1922. Serial No. 561,248.

To all whom it may concern:

Be it known that I, ORA A. RUNKLE, a citizen of the United States, residing at Wooster, in the county of Wayne and State 5 of Ohio, have invented a new and useful Brush, of which the following is an amended specification.

My invention relates to improvements in brushes, and particularly to improvements 10 in fountain brushes, so called, which provide for running water thru the bristles or brush material of any description, for the purpose of washing automobiles, windows, and other surfaces where the application of 15 water is desired to be used in connection with the use of a brush for cleansing purposes. The objects of my invention are, first, to provide a fountain brush of stronger and more durable construction than has heretofore 20 been produced, inexpensive, and easily manipulated; and, second, to so construct the brush material and secure it in the brush head as to provide better means for distributing the water, and more evenly, 25 thru the bristles or brush material, than has been possible heretofore, and, lastly, to more firmly and lastingly secure the bristles or other brush material in the brush head, in connection with the source of water 30 supply, and to fasten the water supply means securely amid the surrounding bristles, or other brush material, in such manner as to distribute the inflow thereto thoroughly and evenly thruout the entire 35 brush head, and prevent floodage therethru, or drippings from the brush while being used, all as hereinafter fully set forth, and as stated in the appended claims.

My invention is illustrated by the accompanying drawings, in which similar letters 40 and figures of reference indicate like parts.

Referring thereto, Fig. 1 is a perspective view of a brush embodying my invention; Fig. 2 is a vertical cross sectional view of 45 the same showing the hose connecting and water distributing means, externally; and Fig. 3 is a detail view showing a cross section of the same with parts in position as shown by dotted lines in Fig. 2.

In the drawings, B indicates the body of 50 bristles or other brush material assembled within a ferrule A, and surrounding the water distributing means, and fastening means for securing the latter together with 55 the brush material within the ferrule. C is a hose connecting nut, such as are com-

monly used; and G is a nipple on which the nut turns in attaching a hose thereto, the nipple having a longitudinal orifice o, thru which water is admitted into the brush 60 material.

E is a plug, which may be made of any suitable material, but preferably of wood, and shaped to conform to the shape of the brush head, either round, square, or oblong, and is driven upwardly thru the central part of the brush material, and cut off squarely across the top of the brush head or ferrule A, as shown in Fig. 3. It is bored from end to end to admit the nipple 70 G tightly therein, and passage of water therethru, and firmly held in position within the ferrule by a sleeve D, which also crowds the bristles together forcibly in its upward drive over the surface of the plug, 75 and prevents the wood of the plug from splitting or becoming loose in the brush head. It also serves to so bend and shape the adjacent bristles B as to cause the water, when admitted into the brush head, to 80 be evenly distributed among them, and such distribution is facilitated by means of a thimble F, the lower end of which is covered, while the sides are perforated with a number of orifices f, as shown in Figs. 2 85 and 3, for the gradual and sidewise escape of the water into the mass of adjacent brush material, in the direction indicated by the arrows in Fig. 3.

It should also be understood, that to accomplish such water distribution, the bristles or brush material are secured in a single bunch formation within the ferrule A by any suitable cement material, and that the sleeve D is to be forced to position over the plug E while the cement is in softened condition, thereby compressing the mass of brush material more firmly and securely together, and shaping the same around the members D and F in the manner stated, to evenly distribute the inflow of water sidewise, and prevent dripping and objectionable overflows at the surface. The thimble F is made of thin sheet metal, and may be driven upwards into the lower edge of the plug E, or otherwise removably secured thereto, and may be of any preferred shape for a spray nozzle, and is provided with small sidewise orifices f, as above stated, immediately below the lower edge of the ferrule, whereby the water is sprayed evenly thru the mass of bristles, and out at the ends 100 105 110 115

thereof, instead of pouring directly thru the more central portion of the brush.

The ferrule may be made of any desired shape, and either open or closed on top, and 5 may be made of any desired flexible material, or other substance, and the several parts may be modified within the spirit of my invention.

Having thus fully described my invention, 10 what I claim as new and desire to secure by Letters Patent is—

1. In a brush of the character described, the combination with a ferrule, a body of brush material assembled therein, a central 15 opening thru the brush material, a tubular plug driven into said opening a limited distance in engagement with the surrounding brush material, a hose connecting nipple secured in the bore of said plug, and a 20 thimble having lateral perforations secured to the lower end of said plug, substantially as set forth.

2. A fountain brush, comprising, in combination, a mass of brush material assembled in cement within a circumferential ferrule, a longitudinal opening thru the mass of said brush material, a tubular plug secured in vertical position within said mass, a hose connecting nipple secured in the bore of said plug in operative engagement with 25 a nut above said mass, a sleeve tightly secured around said plug within the mass of brush material, and a thimble, having a plurality of lateral orifices, secured to the lower end of said plug, substantially as set 30 forth and for the purpose specified.

In witness whereof, I hereunto set my hand this 31 day of March 1923.

ORA A. RUNKLE.

In presence of—
HIRAM SWARTZ.
